(57) **CLAIM**

The ornamental design for a faucet levered spout, as shown and described.

DESCRIPTION

FIG. 1 is a top perspective view of a faucet levered spout showing a first embodiment of my new design;

FIG. 2 is a left side elevational view thereof; the right side elevational view is a mirror image thereof;

FIG. 3 is a front elevational view thereof;

FIG. 4 is a bottom plan view thereof;

FIG. 5 is a rear elevational view thereof;

FIG. 6 is a top plan view thereof;

FIG. 7 is a top perspective view of a faucet levered spout showing a second embodiment of my new design;

FIG. 8 is a left side elevational view thereof; the right side elevational view is a mirror image thereof;

FIG. 9 is a front elevational view thereof;

FIG. 10 is a bottom plan view thereof;

FIG. 11 is a rear elevational view thereof; and,

FIG. 12 is a top plan view thereof.

Broken lines showing internal and external components on FIGS. 1, 2, 3, 4, 7, 8, 9 and 10 are for illustrative purposes only and form no part of the claimed design.
